Primary Examiner—Gary D. Watson**Attorney, Agent, or Firm**—Andrus, Sceales, Starke & Sawall[57] **CLAIM**

The ornamental design for a chair, as shown and described.

DESCRIPTION

FIG. 1 is an isometric view of a chair incorporating our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown at the bottom edge of the chair seat represent the boundary and form no part of the claimed design. All other broken lines are for illustrative purposes only and form no part of the claimed design.
